ABSTRACT

A spinning frame having spindles comprising a fixed part for the admission of slivers, and a rotary spinning bowl part, is so arranged that the bowl can be belt driven at relatively high speeds, and the two parts can be pivoted apart for inspection or cleaning, without handling of driving belts, and so that the drive is automatically disengaged.

SPINNING FRAMES

BACKGROUND OF THE INVENTION

This invention relates to spinning frames having bowl spindles mounted side-by-side and running at high speeds and suitable for making yarns with a prescribed twist from rovings or slivers of textile fibers.

Such spindles are most frequently driven by a belt which is either a friction or tangent belt making contact with a pulley integral with each spindle, or an endless driving belt engaging a pulley on each spindle and a pulley carried by a common drive shaft.

If a friction belt is used, it cannot in practice be driven at a higher linear speed than about 30 m/sec. In the present state of the art, however, there is a tendency to run the spindles at ever-increasing speeds of the order of 50,000 rpm, and great difficulties are encountered in attaining such speeds by direct friction between a friction belt and a pulley, since the spindle pulleys are of insufficient diameter. Moreover, it is necessary for cleaning or inspection to detach the spindles, and the presence of such a friction belt not only hinders access to the spindles but also impedes the execution of the necessary operations.

If separate, endless driving belts are used for each spindle, difficulties in obtaining high speeds are eliminated, since the pulleys can have the appropriate diameters, but dismantling for cleaning and inspection becomes still more difficult.

Moreover, in the case of friction belts and of individual endless belts, the known arrangements involve a first movement for ensuring disconnection of the spindle, and a second movement to enable visual or manual access to the interior of the spindle for the purpose of inspection and cleaning.

An object of the present invention is to provide a spindle mounting and drive therefor so that the aforesaid disadvantages of existing devices are eliminated or reduced, and disconnection and access are possible in a single movement.

SUMMARY OF THE INVENTION

According to the present invention, there is provided a spinning frame of the kind having spindles comprising a fixed part and a rotary part, in which the rotary part of the spindle is mounted freely rotatable on one end of an arm which is pivotable at its other end on a rod at right angles to the axis of the fixed part of the spindle, in such manner as selectively to occupy either a working position wherein it is maintained by releasable locking means and the rotary part of the spindle coacts with the fixed part, or an inspection position wherein the rotary part of the spindle is disengaged from the fixed part, with a rotary drive for the spindle being provided by a step-up belt drive through the intermediary of a small pulley secured to the rotary part and a large pulley freely rotatable on a shaft carried on the arm in the vicinity of said rod, the large pulley being connected to a third pulley of smaller size associated with a friction-driving belt parallel to said rod, so that, when the arm is in its inspection position, the third pulley is disengaged from the friction belt, and when it is in the working position, the third pulley engages the friction belt.

As a result of this arrangement, the step-up belt drive can be used to impart very high speeds of rotation to the spindles without thereby necessarily driving the belt at higher linear speeds than have hitherto been used. In addition, the pivotal movement of the arm carrying the rotary parts of the spindle can be effected without any trouble and without it being necessary even to touch the belts used; the friction belt being, moreover, disconnected by this same pivotal movement, automatically, since the pulley coating therewith is withdrawn from contact therewith, when in the inspection position. In that position, the inside of the bowl spindle is readily accessible so that the inspection and cleaning operations can be conveniently and quickly completed.

In addition, this arrangement allows the provision of very simple braking means which consists merely of an ordinary brake shoe carried on the spindle frame with which the pulley

driven by the friction belt frictionally engages when the carrier arm is moved into the inspection position.

Preferably, the end of the arm carried on the rod is in the form of a spring clip with two arms passing around the rod in such manner as to be detachable therefrom. The assembly consisting of the arm and the whole rotary part of the spindle can thus be handled as a unit together with the step-up belt drive, and this is most convenient for maintenance and repairs.

10 An embodiment of the invention will now be described, by way of example, with reference to the accompanying drawings, in which:

BRIEF DESCRIPTION OF THE DRAWINGS

15 FIG. 1 is a vertical section on the line I—I of FIG. 2 of part of a spinning frame in accordance with the present invention, and shown in the working position;

FIG. 2 is a horizontal section on the line II—II of FIG. 1; and

20 FIG. 3 is a view corresponding to FIG. 1, and in the inspection position.

DETAILED DESCRIPTION OF THE DRAWINGS

25 The section of a spinning frame shown in the drawings comprises a longitudinally extending support 1 along which regularly-spaced spinning spindles are fitted, each as a whole designated by 2.

30 Each spindle 2 comprises a fixed part 3 constituting stationary spinning means attached to the support 1 by screws 4, and a rotary part 5 constituting rotary spinning means arranged immediately underneath the fixed part 3 and carried on an arm 6, of which one end is pivotable on a horizontal rod 7 with the rod being at right angles to the axis of the fixed part 3.

35 The rotary part or bowl 5 of the spindle is attached to a pulley 11, which is freely rotatable on two ball bearings 12, 13 on a central tube 14 secured to a boss 15 held in place at one end of the arm 6 by a nut 16. On the same end of the arm 6, there is fixed by means of the boss 15 and a screw 21, a block 22, on which attached by screw 23 is an annular member 24 which has an annular recess locating a packing ring 26 which bears on a corresponding conical surface 27 of the fixed part 3 of the spindle.

40 The other end of the arm 6 is in the form of a spring clip consisting of an upper jaw 31 formed by bending the end of the arm 6 into the form of a part of a cylindrical surface fitting the cylindrical surface of the rod 7 over nearly a semicircle and a lower jaw 32 consisting of a spring blade attached on the arm 6 by a bolt 33 and which is similarly bent in the form of a part of a cylindrical surface making contact with the cylindrical surface of the rod 7, also over nearly a semicircle. The jaws 31 and 32 end in two beaks 37 and 38, enclosing therebetween a dihedral angle which facilitates the fitting of the clip over the rod 7.

45 The upper jaw 31 is in the form of a fork with prongs 31A and 31B (FIG. 2) which embrace an axially-locating ring 41 fitted to the rod 7 and held thereon by a set screw 42. The lower jaw 32 is similarly forked, with two corresponding arms.

50 The arm 6 is held in the working position shown in FIG. 1, by means of a catch consisting of a leaf spring 45 of which the upper end is attached to the fixed part 3 by a screw 46 while its lower end has a hole 47 fitting over a stud 48 attached to the block 22. By moving the lower end of the spring 45 in the direction of the arrow f1, the spring can be disengaged from the stud 48, so that the arm 6 can drop into the inspection position shown in FIG. 3, by pivoting on the rod 7 in the direction of the arrow f2, with the length of the swing being limited by a stop 51 (FIG. 3) fitted to the support 1.

55 The dimensions and the strength of the spring clip 31 by which the arm 6 is held on the rod 7 are so selected that the arm can be released from the rod by pulling in the direction of the arrow f3, after having released the catch 45. The arm 6 can easily be restored to its original position by placing the

beaks 37, 38 against the rod 7, so that they spread apart when the arm 6 is pushed in the opposite direction to the arrow f3.

The bowl 5 of the spindle is rotated by a friction belt 54 running parallel to the rod 7, a transmission gear comprising the pulley 11, an endless belt 55 passing around the pulley 11, a second pulley 56 around which the belt 55 also passes, and a third pulley 57 integral with the pulley 56 and on which the friction belt 54 bears when the arm 6 is in the working position as shown in FIG. 1 and 2. The pulley 56 is of greater diameter than the pulley 57. The pulleys 56 and 57 are carried on a vertical shaft 58 freely rotatable in two ball bearings 61, 62, in a cup 59 having a threaded end bolt formed by the bolt 33 referred to earlier.

When the arm 6 is in the inclined, inspection position, as shown in FIG. 3, the pulley 57 bears with friction against a brake shoe 71 attached to the lower end of a tongue 72, preferably somewhat elastic, of which the top end is attached to the support 1 by a bolt 73.

The upper, fixed part 3 of the spindle has a nozzle 75 coaxial with the rotary bowl 5 and an aperture 74 for the entry of the rovings of textile fiber to be spun. The nozzle 75 can be inserted into the fixed element 3 from below same (see in particular FIG. 3), when the arm is swung down. It has an axially locating ring 76 bearing against an annular shoulder 77 on the fixed part 3 and an elastic system for angular positioning consisting of two, diametrically-opposed plungers in the form of balls 81 urged by springs 82 inside radial, blind holes 83 in the nozzle 75, with the balls 81 entering partially into corresponding radial holes 85 in the upper portion of the fixed part 3.

The operation of the assembly will now be described.

In the working position shown in FIG. 1 and 2, the rotary bowl 5 is in the upper position ready to coact with the fixed part 3, while the pulley 57 bears against the friction belt 54 in such manner that the latter, through the intermediary of the step-up belt drive 55, rotates the bowl 5.

If it is desired to inspect or clean the bowl 5, it will suffice to release the locking spring 45 and allow the arm 6 to drop against the stop 51 (FIG. 3). This simultaneously disengages the drive, since the pulley 57 moves away from the friction belt 54, brakes the rotary bowl 5 since the pulley 57 makes contact with the brake shoe 71, and presents the bowl 5 in a convenient position, since it is now completely accessible.

The inspecting or cleaning operation having been completed, it suffices in order to return the assembly to the working position, to swing the arm 6 upwards and allow the spring 45 to engage with the stud 48. This automatically releases the brake, since the pulley 57 is moved away from the brake shoe 71 and the drive is engaged by the pulley 57 making contact with the friction belt 54.

When the spindle is thus exposed, the top nozzle 75 can be conveniently removed and refitted.

As has already been explained, the arm 6 and the elements it carries can be completely and instantaneously removed, viz: the rotary part 3 of the spindle, and the step-up belt transmission gear 55.

I claim:

1. A spinning machine having a frame and spindles carried by the frame, each spindle comprising a fixed part and a rotary part a rod carried by the frame and located at right angles to the axis of the fixed part of the spindle, an arm having opposite ends, said rotary part being freely rotatable on one end of the

- arm, the other end of the arm being pivotable on the rod in such manner as selectively to occupy either a working position in which the rotary part of the spindle coacts with the fixed part, or an inspection position in which the rotary part of the spindle is disengaged from the fixed part, releasable locking means cooperable with the fixed part and the movable part to maintain said parts in the working position, a rotary drive for the spindle said drive including a small pulley secured to the rotary part, a shaft carried by the arm adjacent the rod and extending perpendicularly to the arm, a large pulley freely rotatable on said shaft, a third pulley of lesser diameter integral with the large pulley, a friction-driving belt parallel to said rod trained about said third pulley; so that, when said arm is in its inspection position, the third pulley is disengaged from the friction belt, and, when the arm is in the working position, the third pulley engages the friction belt and an endless belt passing around the small pulley and the large pulley.
2. The frame in accordance with claim 1, including a brake shoe with which the third pulley is in contact when said arm is in the inspection position.
3. The frame in accordance with claim 1, in which said other end of said arm is in the form of a two-armed spring clip gripping said rod in such a manner as to form a releasable connection between the arm and the rod.
4. The frame in accordance with claim 1, in which the spindle is on a vertical axis, with said rod and the friction belt being horizontal and the rotary part of the spindle being arranged below the fixed part thereof.
5. The frame in accordance with claim 1, in which the spindle has a nozzle for the admission of the fibers, a socket in the fixed part in which said nozzle is fitted, and quick release and attaching means for the nozzle.
6. The frame in accordance with claim 5, in which the admission nozzle is removable in the direction of the rotary part
- 30 when the arm is in the inspection position, and spring catches holding the nozzle in place in said socket constituting the quick release and attaching means.
7. In a spinning machine having frame means, and at least one spinning unit comprising stationary spinning means carried by the frame means and rotary spinning means including a first pulley and a spinning chamber mounted on the first pulley for rotation therewith, a rod supported by said frame means, an arm having opposite ends, one end of said arm being connected to said rod for swinging movement relative to the stationary spinning means, said first pulley being mounted on said arm for swinging movement therewith between an operative position in which said chamber cooperates with said stationary spinning means to spin a yarn and an inspection position in which said chamber is spaced from said stationary
- 40 spinning means, a second pulley mounted on said arm so as to lie between the first pulley and said rod, said second pulley having two cylindrical length portions of different diameter, a friction drive belt engaged by the smaller diameter portion of said second pulley only when said chamber is in its operative position, and a drive transmission belt trained over said first pulley and the larger diameter portion of said second pulley.
8. The spinning machine according to claim 7, further including fixed brake means positioned on said frame means to be engaged by said smaller diameter portion of the second pulley when the spinning chamber is in the inspection position.
